UNITED STATES PATENT OFFICE.

JAMES MILTON WAUGH, OF CHICAGO, ILLINOIS.

DRAFT-RIGGING FOR RAILWAY-CARS.

No. 818,066.

Specification of Letters Patent. Patented April 17, 1906.

Application filed May 31, 1905. Serial No. 268,135.

To all whom it may concern:

Be it known that I, JAMES MILTON WAUGH, a citizen of the United States, residing at Chicago, in the county of Cook and State of Illinois, have invented certain new and useful Improvements in Draft-Rigging for Railway-Cars; and I do hereby declare that the following is a full, clear, and exact description thereof, reference being had to the accompanying drawings, and to the letters of reference marked thereon, which form a part of this specification.

This invention relates to coupling devices for railway-cars, and more especially to the connections between the draw-bar and draft-sills, whereby a cushioned graduated resistance to shocks occurring in coupling due to variable strains in traction is obtained.

The invention consists in the matters hereinafter set forth, and more particularly pointed out in the appended claims.

In the accompanying drawings, which illustrate two practical forms in which the several features constituting my invention may be embodied, Figure 1 is a plan section taken horizontally through the central axis of the draw-bar, showing the end portions of the draft-sill, the draft-irons thereon, the rear or inner portions of the draw-bar, and the parts constituting my invention associated therewith. Fig. 2 is a vertical section of the same parts taken on line 2 2 of Fig. 1. Fig. 3 is a cross-section taken on line 3 3 of Fig. 1. Fig. 4 is an enlarged detail cross-section taken on line 4 4 of Fig. 3. Fig. 5 is a plan section corresponding generally with Fig. 1, showing a somewhat different form of construction embodying my invention. Fig. 6 is a cross-section taken on line 6 6 of Fig. 5.

As shown in the said drawings, Figs. 1 to 4, A A indicate the end portions of the draft-sills, which form part of the floor-frame of the car, and B designates a draw-bar which is located centrally between the draft-sills and is provided with a yoke C, formed by means of a bar of steel bent between its ends into a U form and having its parallel side parts arranged horizontally and parallel with each other with its ends overlapping the top and bottom surfaces of the inner end of the draw-bar, to which it is secured by means of vertical bolts c c.

D D indicate draft-irons which are secured to the inner surfaces of the draft-sills. Said draft-irons D D have the form of recessed or flanged plates secured by mortises and bolts

to the inner surface of the draft-sills A. Each of said plates D is provided with an upper horizontal longitudinal flange D' and with a lower horizontal longitudinal flange D², the latter being formed by means of a separate bar removably secured to the draft-iron by means of bolts d d, Fig. 2. Near their ends the said draft-irons are provided with inwardly-extending vertical ribs or flanges D³ D⁴, the inner faces of which form bearing faces or shoulders d' d². Mounted on the draft-irons between the flanges D' D⁴ are upright sliding spacing-blocks E E, the opposite sides of which form bearing-shoulders e e', which face toward the bearing-shoulders d' d² on the draft-irons.

F F F indicate transversely arranged spring-plates which pass through the yoke of the draw-bar, and the ends of which extend into the recesses of the draft-irons formed by and between the flanges D³ D⁴ and the spacing-blocks E. Said spring-plates are arranged in four sets or groups, as indicated by F' F² F³ F⁴, of which the sets F' F⁴ may be called "follower-plates" and the sets F² and F³ "cushioning-plates." The set F' of follower-plates is located in contact with the inner end of the draw-bar D, the set F⁴ of follower-plates is in contact with the inner end of the yoke C, and the sets F² and F³ of cushioning-plates are located adjacent to each other and are separated at their ends by the said spacing-blocks E E, which bear at their opposite sides against the ends of the said sets of cushioning-plates. The lower flanges or bottom plates D² D² of the draft-irons serve to support the spring-plates constituting the sets of cushioning and follower plates in position and when detached enable said plates to be readily dropped out of their places in the recesses of the draft-irons.

The spacing-blocks E E are shown in Figs. 1 to 4 as supported in place by means of vertical and horizontal lugs e² e³ on the lower outer corners of said blocks, the vertical lugs e² being arranged to extend downwardly between the inner margins of the lower removable plates D² and the vertical walls of the draft-irons and the horizontal lugs e³ extending horizontally outward from the lugs e² beneath the lower edges of the said vertical walls of the draft-irons. Said lugs e² and e³ thus arranged serve to hold the blocks from sliding forwardly out of place and also from tipping forward at their upper ends, while at the same time permitting the blocks to move freely in a direction endwise of the draft-

irons. Between the said follower-plates F' and the cushioning-plates F^2 is located a spacing-plate G , and between the cushioning-plates F^3 and the follower-plates F^4 is located a like spacing-plate G' . Said spacing-plates G and G' engage and bear against the adjacent spring-plates on either side thereof, at points centrally between the ends of said plates, and said spacing-plates are convexly curved on their opposite faces, or, in other words, are made much thinner at their ends than at their middle parts. As a means of supporting or holding in place the said spacing-plates G G' the latter are each made in two parts g g' , which are applied at opposite sides of and secured to supporting-plates g^2 g^3 , the ends of which enter the recesses in the draft-irons and are held or supported in position by engagement with the top and bottom flanges of the draft-irons in the same manner as are the spring-plates F . The spacing-plates G G' are thus held in proper position with respect to the spring-plates at either side thereof, while at the same time they are free to be moved or shifted in a direction endwise of the draft-irons. As shown in the accompanying drawings, the parts g g' of the spacing-plates are joined with each other and connected with the supporting-plates by means of studs g^4 g^4 on the part g , which passes through holes in the supporting-plates and enter holes or sockets in the other part g' , as clearly seen in Fig. 4.

The sets F' and F^4 of spring follower-plates embrace or include a greater number of plates than the sets F^2 F^3 of cushioning-plates or are otherwise so made as to afford greater resistance to bending or flexure than to the cushioning-plates. The outer ends of the inner plates of the sets F^2 F^3 of cushioning-plates, which are adjacent to the spacing-blocks E E , are normally in contact with the said blocks, which serve to prevent the approach of the outer ends of the said sets F^2 F^3 toward each other. The outer ends of the external plates of the sets F' and F^4 of follower-plates are likewise normally in bearing contact with the ribs D^3 D^4 .

In the operation of the parts thus described supposing that inward pressure is brought upon the draw-bar B , such as occurs when the cars come forcibly together in coupling, said draw-bar B , with its yoke C , are forced inwardly, and the inner end of the draw-bar, acting on the central part of the adjacent set F' of the follower-plates, carries that set bodily inward and with it the central part of the set F^2 of cushioning-plates, to which pressure is transmitted by the spacing-plate G . In the preliminary inward movement of the draw-bar the inner set F^4 of the follower-plates is not shifted, nor the plates thereof bent; but as the sets F^2 F^3 of cushioning-plates have greater flexibility than the sets F' F^4 of follower-plates and as

the outer ends of the cushioning-plates will be held at the same distance apart by the spacing-blocks E E when the central parts of the plates in the set F^2 are thrust inwardly the inward pressure of the outer ends of the plates of the set F^2 will be transmitted to the outer ends of the plates of the set F^3 , and as the two sets of cushioning-plates are of equal stiffness they will be equally flexed or bent, the outer ends of the plates in the set F^2 being bent toward the outer ends of the set F' of follower-plates, while the outer ends of the plates in the set F^3 of cushioning-plates will be similarly bent toward the ends of the plates in the set F^4 of follower-plates. This bending of the sets F^2 F^3 of cushioning-plates will continue until their end portions strike or come in contact with the outer ends of the sets F' F^4 of follower-plates, and further flexure of the cushioning-plates cannot then take place without the follower-plates in the set F' being flexed inwardly or in the same direction as those of the set F^2 of cushioning-plates. Moreover, when the cushioning-plates have come in contact at their ends with the follower-plates they will come in contact with each other at their central parts, and further inward movement of the draw-bar will be resisted by the set E^4 of the follower-plates, which latter if the pressure coming on the draw-bar be unusually great will finally be bent or flexed inwardly by the pressure transmitted thereto through the central parts of the set F' of follower-plates, the cushioning-plates, and the spacing-plates G and G' . It will be seen, moreover, that as soon as the outer ends of the cushioning-plates of the set F^3 come in contact with the follower-plates of the set F^4 and the ends of the set F^2 of cushioning-plates are similarly brought in contact with the set F' of follower-plates then the inward movement of the outer ends of the follower-plates in the set F' will be resisted by solid abutments afforded by the outer ends of the sets F^2 F^3 of cushioning-plates, the spacing-blocks E , and the set F^4 of follower-plates.

It follows from the above that as the draw-bar is forced inwardly its inward movement will be resisted by the two sets F^2 F^3 of cushioning-plates, and that if the pressure or shock on the draw-bar is unusually great the sets F' F^4 of follower-plates will yield or bend so that a graduated and gradually-increasing or cushioning resistance will be afforded to the inward movement of said draw-bar.

The graduated cushioned resistance of the outward movement of the draw-bar will be afforded by like action of the groups of plates when strain comes upon said draw-bar in a direction to carry it outwardly, as occurs when the couplings are subjected to tension in the starting of the strain.

It will be understood that in the operation of the devices described as the sliding spac-

ing-blocks E E are in contact at both sides thereof with the ends of the sets F² F³ of cushioning-plates endwise movement of the draw-bar in either direction will be opposed by the action of said cushioning-plates, both sets of which are simultaneously and uniformly flexed in the movement of the draw-bar in either direction. After the ends of the sets F² F³ of cushioning-plates are brought into contact at their ends with the sets F' F² of follower-plates and the two sets of cushioning-plates are brought together at the center thereof further inward movement of the draw-bar will be resisted by the set F² of cushioning-plates and both sets F' F⁴ of follower-plates. Like action takes place when outward tension is exerted on the draw-bar, the yoke C in that case acting on the set F⁴ of follower-plates and serving to first flex the sets F² F³ of cushioning-plates and then bring the sets F' F⁴ of follower-plates jointly into action.

In the modified construction shown in Figs. 5 and 6 the draft-sills A, draw-bar B, yoke C, and draft-irons D D are arranged and constructed in the same manner as before described; but the spaces between the flanges D³ D⁴ of the draft-irons are longer than in the construction shown in Fig. 1. In this instance two sets of spacing-blocks H H' and four sets of spring cushioning-plates I I are employed, the several sets of cushioning-plates being indicated by I', I², I³, and I⁴. In this instance, moreover, rigid follower-plates J J' are arranged in contact with the inner end of the draw-bar B and the yoke C and extend at their ends into the recesses of the draft-irons into contact with the flanges D³ D⁴. Moreover, a spacing-plate K is interposed between the follower-plate J and the outermost set I' of cushioning-plates. A like spacing-plate K' is interposed between the two intermediate sets of cushioning-plates I² I³, and a third spacing-plate K² is interposed between the inner set of cushioning-plates I⁴ and the follower-plate J'. The spacing-blocks H H' and the spacing-plates K K' K² correspond generally in arrangement and function with the spacing-blocks E E and spacing-plates G G'. (Shown in Fig. 1.) In this instance the spacing-plates K K' K² are made in two parts or halves and are attached to supporting-plates k k' k², corresponding with the plates g² g³ shown in Fig. 1. The spacing-blocks H H' in this instance are supported in proper relative position and held in place by being attached to the ends of transverse plates h h', said plates h h' serving to hold the blocks at a proper distance apart, so that said plates and blocks may be inserted in place within the recesses of the draft-irons in the same manner as are the spring-plates. The sets I' I² of cushioning-plates are of equal strength or stiffness, being composed of a corresponding number of the individual plates I I, while the

sets I³ I⁴ are also of equal strength or stiffness but possess considerably greater stiffness than the sets I' I². In the particular construction shown the sets I' I² consist each of five plates of equal thickness, while the sets I³ I⁴ consist of seven plates of equal thickness. 70

In the operation of the device shown in said Figs. 5 and 6 the two weaker sets of cushioning-plates I' I² come into operation before 75 the stiffer sets of plates I³ I⁴ are bent or flexed, and this is true in the movement of the draw-bar in either direction. The spacing-blocks H H' are about twice the thickness of the cushioning-plates K and K², so that when the 80 cushioning-plates are flexed sufficiently to come in contact at their ends with the follower-plates said cushioning-plates will come in contact at their middle parts with the plates h h'. The spacing-plate K' is twice as 85 thick as the spacing-plates K and K². The operation of these parts is as follows: When inward stress or pressure comes upon the draw-bar B, the outermost follower-plate J is moved or carried inward from its normal 90 position, and at the beginning of such inward movement pressure is transmitted from said follower-plate J by the spacing-plate K to the set I' of cushioning-plates and flexes the central parts of the plates of said set I' inwardly, 95 while pressure of the outer ends of said set I' on the movable spacing-blocks H H' brings equal pressure upon the outer ends of the set I², so that both sets I' and I² of cushioning-plates are flexed to an equal extent. The 100 flexure or bending of the sets I' I² continues until the outer ends of the set I' are brought into contact with the ends of the follower-plate J. At the same time that this occurs the middle portions of the said sets I' I² come 105 in contact with the plate h, connecting the spacing-blocks H H'. After the plates of said sets I' I² have been flexed so far as to bring them to their maximum flexure inward pressure of the draw-bar will be transmitted 110 through the central portions of said sets I' I² and the spacing-plates K K' directly to the middle part of the set I³ in a direction to flex the latter inwardly, and as said set I³ is so flexed inwardly the outer ends thereof, acting on the outer ends of the set I⁴ through the movable spacing-blocks H' H', will bend or 115 flex the set I⁴ to an extent corresponding with the flexure of the set I³. When the set I⁴ has been flexed to such an extent as to bring its 120 ends into contact with the ends of the inner follower-plate J' and the sets I³ and I⁴ have been brought into contact at their middle parts with the supporting-plate h', further 125 flexure of any of the plates is prevented, and further inward movement of the draw-bar will be resisted by the follower-plate J and by the sets I' I² of cushioning-plates, which latter sets of plates will aid in resisting further inward movement of the draw-bar, it being 130

manifest that at this time their outer ends will be held from shifting toward the inner ends of the draft-irons because the outer ends of the set I^4 will be in contact with the outer ends of the follower-plates J' , the spacing-blocks $H' H'$ will be in contact with the outer ends of the set I^4 , the outer ends of the set I^3 will be in contact with the spacing-blocks $H' H'$, the outer ends of the set I^2 will be in contact with the outer ends of the set I^3 , the spacing-blocks $H' H'$ will be in contact with the outer ends of the set I^2 , and the outer ends of said set I' will bear directly on said spacing-blocks $H H$.

When outward strain or stress comes upon the draw-bar in a direction to pull or draw the same outwardly, the operation will be the same as above described, with the exception that the follower-plate J' will move in the recesses of the draft-irons while the follower-plate J will rest in contact with the flanges $D^3 D^3$, it being of course understood that by reason of the greater flexibility of the sets $I' I^2$ of cushioning-plates the latter will be first bent or flexed in the preliminary movement of the draw-bar and that the flexure of the sets $I^3 I^4$ of cushioning-plates will not take place until the sets $I' I^2$ have substantially reached the position of maximum bending or flexure.

It is to be noted in connection with the form of construction shown in Fig. 5 that two sets of spring follower-plates corresponding with the sets $F' F^4$ of Fig. 1 may be substituted for the rigid follower-plates $J J'$ and when so substituted will operate in the same manner as do the said sets $F' F^4$ illustrated in Fig. 1. It will, moreover, be apparent that if sets of spring follower-plates corresponding with the plates $F' F^4$ be substituted for the rigid follower-plates $J J'$ in the construction shown in Fig. 5 then the general structure of Fig. 5 will correspond with that of Fig. 1, with the exception that the two coacting sets of cushioning-plates, which are of equal flexibility and are equally and oppositely bent in operation, as above described, will be duplicated, as in the construction shown in Fig. 5. In other words, two sets of spring cushioning-plates corresponding in operation with the two sets $F^2 F^5$ of Fig. 1, but of greater strength or stiffness, is in the construction shown in Fig. 5 added to the two sets shown in Fig. 1 without any difference in operation of the sets constituting each pair of sets, but with the result of giving a greater capacity for end-wise movement of the draft-bar without an undue extent of flexure in either of the sets of cushioning-plates. It will also be manifest that the operation of the pairs of like or corresponding sets of spring-plates will be substantially the same, whether the members in contact with the inner end of the draw-bar and the inner end of the yoke C have the form of rigid follower-plates, like the plates $J J'$, or

have the form of sets of spring-plates, like the sets $F' F^4$ shown in Fig. 1.

A draft-rigging constructed as hereinbefore set forth has the advantage not only of being exceedingly cheap to construct, easy to keep in repair, and much less liable to breakage than draft-riggings in which coiled springs are used, but because the effect of recoil is greater lessened for the reason that the bending or flexing of the sets of plates is accompanied by the frictional resistance due to the sliding of plates upon each other at their end portions, such frictional resistance not only tending to retard the flexure of the sets of plates when bending stress is brought thereon, but to also retard the straightening movement of the plates when the pressure is released, thereby preventing quick or sudden recoil movements of the draw-bar in either direction.

I claim as my invention—

1. The combination with shouldered draft-irons and a draw-bar provided with a yoke, of two like sets of spring cushioning-plates, sliding spacing-blocks interposed between and in contact with the ends of the sets of cushioning-plates, follower-plates interposed between the sets of cushioning-plates and the draw-bar and yoke, and spacing-plates interposed between and in contact with the follower-plates and the centers of the sets of cushioning-plates.

2. The combination with shouldered draft-irons and a draw-bar provided with a yoke, of a plurality of sets of spring cushioning-plates arranged in pairs, the sets constituting such pairs being of like stiffness and the sets in the different pairs differing in stiffness, sliding spacing-blocks interposed between and in contact with the ends of the two sets of cushioning-plates of each pair, follower-plates interposed between the external sets of cushioning-plates and the draw-bar and yoke, and interposed spacing-plates having bearing contact with the centers of the sets constituting each pair and with the follower-plates.

3. The combination with shouldered draft-irons and a draw-bar provided with a yoke, of two like sets of spring cushioning-plates, sliding spacing-blocks interposed between and in contact with the ends of the two sets of cushioning-plates, two sets of spring follower-plates interposed between the sets of cushioning-plates and the ends of the draw-bar and yoke, and spacing-plates interposed between and bearing on the centers of the sets of cushioning-plates and the sets of spring follower-plates.

4. The combination with shouldered draft-irons and a draw-bar provided with a yoke, of two like sets of spring cushioning-plates, sliding spacing-blocks interposed between and in contact with the ends of the two sets of cushioning-plates, spring follower-plates

interposed between sets of cushioning-plates and the ends of the draw-bar and yoke, and spacing-plates interposed between and bearing on the centers of the sets of cushioning-
5 plates and the sets of follower-plates, the shoulders on the draft-irons engaged by the spring follower-plates being inclined or beveled.

In testimony that I claim the foregoing as my invention I affix my signature, in presence 10 of two witnesses, this 22d day of May, A. D. 1905.

JAMES MILTON WAUGH.
